UNITED STATES PATENT OFFICE

BURTON S. FLORADAY, OF TOLEDO, OHIO, ASSIGNOR TO THE DURA COMPANY, OF
TOLEDO, OHIO, A CORPORATION OF OHIO

DOOR LATCH

Application filed May 26, 1930. Serial No. 455,810.

The invention relates to latches and more particularly latches for motor vehicle doors. The invention has for one of its objects the provision of an improved latch which may be economically manufactured. The invention has for other objects to so construct the latch that the latch bolt retains in operative position the actuating means for normally moving the bolt to extended position; the latch bolt has means which is in operative relation to the retracting means for the bolt and which constitutes a cover for the means for normally returning the bolt; and the latch bolt carries the bolt returning means.

With these and further objects in view, an embodiment of my invention is shown in the accompanying drawing and will be more fully hereinafter described and the invention defined in the claims.

In the drawing:

Figure 1 is a side elevation of a latch showing an embodiment of my invention;

Figure 2 is a top view thereof;

Figures 3 and 4 are cross sections, respectively, on the lines 3-3 and 4-4 of Figure 1.

The latch embodying my invention is designed particularly for use in motor vehicle doors and has the case plate 1, which at its forward edge is provided with the transverse flange 2. This flange is formed with a rectangular opening 3 and an ear 4 cut from the opening for receiving and guiding the nose 5 of the latch bolt. The nose at its rear end is secured, as by means of the rivet 6, to the sheet metal member 7, which with the nose forms the bolt. The rear end of this sheet metal member 7 has the longitudinally extending slot 7' to receive the shouldered rivet or pin 8, which extends through and is secured to the case plate, the arrangement being such that this rivet with the case plate and its front flange serve in guiding the bolt during its reciprocation.

For retracting the bolt, I have provided the outside manually operable retracting means, which includes the roll-back 9 having the front end of its hub journaled in the case plate and inside manually operable retracting means, which includes the link 10 adapted to be connected to a remote control handle and

secured at its forward end to the shouldered rivet or pin 11 which extends through the slot 7' and connects the bolt to the link. 12 is a suitable spiral spring which normally returns and holds the bolt in its extended position. 55

The sheet metal member 7 forming part of the bolt is provided with the extension 13 which is laterally offset from the portion of the member directly secured to the bolt nose and also from the case plate and which is formed with the forwardly opening slot 14 through which extends the rear end of the hub of the roll-back 9. The upper portion of the extension is formed with the transverse flange 15 for engaging the actuating portion of the roll-back 9 so that upon actuation of the roll-back the extension serves in retracting the bolt. The spring 12 is located between the case plate and the extension and has one end secured between the ears 16 struck out from the extension and its other end engaging the ear 17 struck out from the case plate. With this arrangement it will be seen that the extension forms the connection between the roll-back and the bolt for retracting the bolt and it at the same time serves in retaining the spring in operative position. 75

For locking the bolt from retraction through the outside retracting means, I have provided the dog 18, which is pivoted upon the case plate and is located above the extension 13 and has its front end engageable with the roll-back 9 when the dog is in operative position. Swinging of this dog to an inoperative position where it clears the roll-back is limited by the ear 19 struck out from the case plate and engageable with the opposite end of the dog. I have also provided the dog 20 which is pivoted upon the case plate below the bolt and which is adapted to be 80 swung into the recess 21 in the lower edge of the sheet metal member 7 for locking the bolt in its extended position. 90

What I claim as my invention is:

1. In a latch, a case plate, a latch bolt movable on said case plate, retracting means on said case plate for said bolt, means engaging said case plate for normally holding said bolt in extended position, and a plate-like extension rigid with said bolt and projecting from 100

one side thereof, said extension being laterally offset from the bolt in a direction to form a space between the same and case plate for receiving said bolt holding means.

5 2. In a latch, a case plate, a latch bolt movable on said case plate, an extension upon said bolt offset from the latter to form a space between the same and case plate, and a spring carried by the extension within the space aforesaid and engageable with the case plate for normally holding said bolt in extended position.

10 3. In a latch, a case plate, a latch bolt movable on said case plate, actuating means on the case plate for retracting said bolt, means upon said bolt arranged to be actuated by said retracting means to retract said bolt including an extension projecting from one side of the bolt and offset relative to the case plate to form a space therebetween, and means for moving said bolt to its extended position including a spring carried by the extension within the space between the latter and case plate and having a portion engageable with the latter.

15 4. In a latch, a case plate, a latch bolt movable on said case plate, an extension upon said bolt projecting laterally from one side thereof in spaced relation to the case plate, a roll-back on said case plate and engageable with said extension for retracting the bolt, and means located within the space between the extension and case plate including a resilient member carried by the extension and engageable with the case plate for normally urging said bolt to its extended position.

20 5. In a latch, a case plate, a latch bolt movable on said case plate, an extension upon said bolt forming with the adjacent side of the case plate a space, and yieldable means carried by the extension within the space aforesaid and engageable with a part of the case plate for normally holding said bolt in extended position.

25 6. In a latch, a case plate, a latch bolt having a shank portion slidably contacting with the case plate, retracting means on said case plate for the bolt, an extension upon said shank offset from the latter in a direction to form with the case plate a space, and means located within the space for normally holding said bolt in extended position.

30 7. In a latch, a case plate, a latch bolt movable relative to the case plate, an extension upon the bolt spaced laterally from the case plate, and yieldable means carried by the extension within the space between the latter and case plate and operable to normally hold said bolt in extended position.

35 60. In testimony whereof I affix my signature.
BURTON S. FLORADAY.
